WRINGER AND THE LIKE

Walter L. Kauffman, II, Erie, Pa., assignor to
Lovell Manufacturing Company, Erie, Pa., a
corporation of Pennsylvania

Original application February 6, 1936, Serial No.
62,606. Divided and this application June 9,
1939, Serial No. 278,300.

1 Claim. (Cl. 68—262)

Clothes wringers are ordinarily provided with wringer rolls which are subjected to a yielding pressure. The wringer is usually provided with means for adjusting the initial pressure on the rolls, but as different qualities of material are passed through the wringer the amount of separation of the rolls and the arrangement of springs exerting the pressure bring about wide variations of pressure. It is desirable that the operator be informed of the pressure operating on the rolls, not only initially but with relation to the various separations to which the wringer is subjected. The present invention is designed to provide means for this purpose. Features and details of the invention will appear from the specification and claim.

A preferred embodiment of the invention is illustrated in the accompanying drawing as follows:

20 Fig. 1 is a front elevation of a wringer partly in section.

Fig. 2 a section on the lines 2—2 in Figs. 1 and 4.

Fig. 3 a section on the lines 3—3 in Figs. 1 25 and 4.

Fig. 4 an enlarged view, partly in section, of a releasing device.

1 marks the base of the wringer frame, 2 the side stiles and 3 the top bar. One end of the top bar is secured on the stiles by interlocking shoulders 4 and at the opposite end by a safety release 5, the safety release being of the type described in my application, Serial Number 621,918, filed July 11, 1932. 6 marks the lower roll, 6a 30 the upper roll, and 7 the shaft of the lower roll which as shown is the drive shaft. The shaft 7 is journaled in bearings 8 carried by brackets 9 in the stiles. The upper roll has the shaft 10 which is journaled in bearings 10a slidingly 35 mounted in the stiles. A spring 11 exerts pressure on the upper bearing blocks. A screw 12 operates through a nut 13 in the top bar and is

swiveled at 12a on the spring. The screw is operable by a handle 14. These parts are, or may be, of common construction.

A movable base 15 is provided with a collapsing fluid receptacle 16. The opposite end of the receptacle is mounted by a clip 17 on the spring. The receptacle is connected by a tube 18 with a tube 19 of a fluid pressure indicator 20 in which the pointer 21 indicates the pressure to which the fluid in the collapsible receptacle is subjected. 10 This fluid pressure is responsive to the pressure exerted on the spring and the pressure indicator is calibrated with relation to the fluid pressures incident to pressure exerted by the spring on the collapsible container so that the pressure exerted 15 by the spring on the rolls is at all times indicated on the pressure indicator.

While I have exemplified my invention as applied to wringers, I wish it to be understood that the invention extends to wringers and the like in 20 which there are squeezing rolls utilized for operating upon clothes.

This application is a division of application No. 62,606 filed February 6, 1936.

25 What I claim as new is:

In a wringer and the like having a frame, wringer rolls mounted in the frame, one of which rolls is movable, and means exerting yielding pressure on both ends of the movable roll so as to urge the latter toward the other roll, said 30 means substantially equalizing the pressure at the opposite ends of the rolls with varying degrees of movement of the roll; the combination with said means of a collapsible fluid container having a base on the frame and pressure engagement with the means, said engagement sustaining the initial and cumulative pressure on both ends of the roll, and a fluid pressure indicator connected with the container and indicating the roll pressure.

40 WALTER L. KAUFFMAN, II.
